Des. 212,149
Patented Sept. 3, 1968

212,149

BED ROLL

Johan E. Tuvert, Kungsportsavenyen 22,
Goteborg, Sweden

Continuation-in-part of design application Ser. No. 86,778,
Aug. 31, 1965. This application Nov. 14, 1966, Ser. No.
4,646

Term of patent 14 years

(Cl. D5—2)

FIG. 1 is a perspective view of the bed roll.

FIG. 2 is an end elevational view of the head end of the bed roll looking to the left in FIG. 1.

FIG. 3 is a top plan view of the bed roll in reduced scale.

FIG. 4 is a bottom plan view of the bed roll in reduced scale.

This application is a continuation-in-part of application Ser. No. D. 86,778, filed Aug. 31, 1965, now abandoned.

I claim:

The ornamental design for a bed roll, as shown.
